DISPLAY CASE AND REMOVABLE
CONTAINER THEREFOR

Harvey C. Holderle, Frederick S. Holderle, Frederick W. Holderle, and Carl L. Holderle, Rochester, N. Y.

Application January 20, 1950, Serial No. 139,754

4 Claims. (Cl. 312—322)

1

This invention relates to a display case and removable container therefor, and has for its purpose to afford a practical form of merchandise container that is positionable and readily accessible within the case and from which the contents may be easily taken to fill orders, the container being quickly and conveniently removable from the case when empty and ready to be refilled.

Heretofore in merchandising candy, the general practice has been to place the candy in receptacles or between partitions fixed within the case, which has made it difficult to keep the display case clean and sanitary and also troublesome to refill when the supply within the case is exhausted, and where removable containers have been placed within the case, it has not been easy to remove the contents from the containers when located within the case, and it is a particular purpose of the invention to afford a container that is easily accessible to remove its contents when positioned within the display case, which can readily be moved to any location in the candy case, and which can quickly be removed when empty and taken to the stockroom to permit cleaning and refilling in a convenient manner, thus eliminating the necessity of handling the candy several times.

More particularly the invention is intended to provide a container that is easily removable from a display case and is constructed in such a way as to utilize a maximum capacity of the case, the container being provided with a movable cover arranged to be locked over the filling opening when the container is filled and being transported from one point to another and to be positioned on top of the container so as not to interfere with removal of its contents when the container is positioned within the display case.

To these and other ends, the invention consists in the construction and arrangement of parts that will appear clearly from the following description when read in conjunction with the accompanying drawings, the novel features being pointed out in the claims following the specification.

In the drawings:

Fig. 1 is a transverse vertical sectional view of a display case with a merchandise container positioned therein constructed in accordance with a preferred embodiment of the invention; and showing the cover in closed position in full lines and in open position in dotted lines;

Fig. 2 is a rear elevation of the same;

Fig. 3 is a plan view of the container;

Fig. 4 is a view in side elevation of the same;

2

showing the cover closed in full lines, and in dotted lines a position of the cover as it is moved from closed to open position;

Fig. 5 is a detail sectional view on line 5—5 of Fig. 4;

Fig. 6 is a rear elevation of the container illustrated in Figs. 3 and 4, partially broken away, and

Fig. 7 is a detail sectional view on line 7—7 of Fig. 6.

10 The invention is illustrated in connection with a display case such as illustrated in copending application Serial No. 139,753, filed January 20, 1950, and including a base having attached thereto a bottom wall 1 with an abutment 2 at its front portion, and a lower channel including a rear inclined portion 3, bottom 4, and vertical front portion 5, while 6 designates the top wall of the display case including a depending front portion 7 which carries an upper channel including an inclined bottom wall 8, rear inclined wall 9, and inclined front wall 10, the top wall of the case and the walls forming the top channel being supported by suitable uprights or standards 11 attached to the base in any convenient way.

20 The front of the display case is open between the upper and lower channels just described, and 12 indicates one of a series of removable closures for said opening, each closure comprising a receptacle with a removable cover adapted to receive merchandise for display purposes and to be detachably arranged between the upper and lower channels and constitute a removable front wall or panel for the display case.

30 35 The removable closure receptacle just described is designed to receive and display candy or other merchandise contained within the case and this application relates more particularly to a container removably located within the case and adapted to carry a supply of candy or other merchandise corresponding to that displayed in one or more of the receptacles 12 behind which the container would normally be positioned;

40 45 50 55 13 designates an upstanding portion at the rear of the bottom wall 1, forming a stop against which a slideable door, not shown, can travel, the door being supported and movable in a suitable track 14 at the top, the slideable door supporting means at the rear of the display case constituting no part of the invention and being old in the art. Removably positionable within the display case is a metal container including a front wall having a vertical portion 15 engageable with the abutment 2, and an upwardly and rearwardly inclined portion 16 that connects with a horizontal

tal top wall 17, while the bottom wall of the container includes a horizontal portion 18 terminating in an upwardly inclined rear portion 19, the container including side walls 20 to which top, bottom, and front walls are attached in any convenient manner.

The top wall 17 is provided with its rear edge with a supporting rod 21 the ends of which extend somewhat beyond the side walls of the container to afford trunnions, the rod 21 being attached to the top wall in any suitable fashion, and the upwardly inclined rear part 19 of the bottom wall is likewise provided with a supporting rod 22 attached thereto in any suitable fashion and having end portions or trunnions which extend beyond the side walls of the container as shown. The container is accessible through the opening at its rear between the top and bottom walls and is provided with a cover that is movably associated with the container and adapted to be moved to uncover the opening at the rear of the container, when located in the display case, or to be locked in closed position over the opening when carrying the filled container from a storeroom to the display case.

To accomplish these objectives, there is provided a cover, as indicated at 23, provided at opposite side edges with channels 24 which embrace the trunnions or ends of rod 21, while 25 designates an inwardly bent flange at the front or upper end of the cover adapted to overlie the rear portion of the top wall and rod 21 to limit downward movement of the cover when the latter is in closed position as shown in Fig. 4 in full lines. Thus the cover can pivot and slide on the trunnions or terminal portions of the rod 21 and is movable from its horizontal position overlying the top wall 17, as shown in dotted lines in Fig. 1, to its lowered position as illustrated in Fig. 4, in which the container is closed by the cover. When closing the cover, it is swung as indicated by dotted lines in Fig. 4 until the lower portion of the cover engages the rear edges of the side walls of the container whereupon the cover can be moved downwardly and the channels 24 which are open at their lower ends engage and slide downwardly over the trunnions or terminal portions of the lower rod 22, to interlock therewith in the manner shown in Fig. 7 and prevent outward swinging movement of the cover. To open the container, the cover must first be moved in a vertical direction far enough to disengage the channels 24 from the ends of the lower rod 22, after which the cover can be swung upwardly to its horizontal position and moved forwardly over the top wall 17 to the position shown in dotted lines in Fig. 1.

26 designates a flange or stop portion carried by the inner surface of the cover and cooperating with the top and bottom walls of the container to limit forward and downward movement respectively of the cover, while 27 designates a handle portion on the outer surface of the cover for manipulating the same to either of its positions.

The upwardly and rearwardly inclined front wall 16 of the container conforms generally to the inclination of the front panel or receptacle 12 so that the container can utilize the capacity of the case to a maximum for holding merchandise while the inclined rear portion 19 of the bottom wall of the container enables readily scooping candy or like merchandise from the container.

It will be understood that when a container is empty, it is removed from the display case and

can then be cleaned and filled to the desired level with candy or other merchandise after which the cover is closed to prevent loss of the contents while carrying the container to the display case.

5 The container is then positioned in the case in the manner shown in Fig. 1, with its front vertical wall 15 engaging the abutment 2 at the forward part of the display case to limit movement of and position the container while the rear part of the container can be moved downwardly in front of the upstanding wall or portion 13 at the rear of the display case, as shown in Fig. 1, the container being thus held in the case against accidental displacement and requiring upward movement at its rear before removal.

After the container is thus positioned, the cover can be moved upwardly and swung about the top wall 17 in the manner indicated in dotted lines in Fig. 4 and then moved forwardly to the position shown in dotted lines in Fig. 1 so that the contents of the container are readily accessible from the rear of the display case, which is protected by the usual sliding doors not shown, the arrangement being such that the position of the container does not interfere with the normal movement of the sliding doors. The container cover can be left in its uppermost position while the container is in the case, and it is not necessary to lower the cover until the container is to be removed to receive a fresh supply of merchandise, although if desirable, the cover can be moved into position to close the container and protect its contents while the container is located within the display case.

35 While the invention has been described with reference to the particular construction herein disclosed, it is not confined to the details illustrated and this application is intended to cover such changes or modifications as may come within the purposes of the invention and the scope of the following claims.

We claim:

1. The combination with a display case, of a removable container including a horizontal top wall having a supporting rod attached at its rear and extending beyond the side edges of said top wall, a bottom wall including a horizontal portion and an upwardly inclined portion at the rear thereof, and a cover having means at opposite sides pivotally and slidably supported on the ends of said rod and movable from a position overlying said top wall by a swinging and downwardly sliding motion to a position interlocked with said upwardly inclined portion of the bottom wall, the cover when in said last mentioned position being held against swinging movement until first moved vertically by sliding.

2. The combination with a display case, of a container removably positionable within said display case and including a top wall having a supporting rod attached at its rear and extending beyond the side edges of said top wall, a bottom wall including a horizontal portion and an upwardly inclined rear portion, a supporting rod attached to the rear of said upwardly inclined portion and extending beyond the side edges thereof, a cover having channels at opposite sides slidably and pivotally supported on the ends of said upper rod and slidably engageable with the ends of said lower rod, and means in the display case engaging and limiting movement of the container.

3. The combination with a display case, of a container having a horizontal top wall having a supporting rod attached at its rear and extending

beyond the side edges of said top wall, a bottom wall including a horizontal portion and an upwardly inclined portion at the rear thereof, a supporting rod attached to the rear of said upwardly inclined portion and extending beyond the side edges thereof, and a cover having means at opposite sides pivotally and slidably supported on the ends of said rod and movable to a position overlying said top wall or by a swinging and downwardly sliding motion to a position in rear of said upwardly inclined portion of said bottom wall, said means on the cover being engageable with the ends of said rod on the upwardly inclined portion and acting to prevent swinging movement of the cover when in said rear position until it is first moved vertically by sliding.

4. The combination with a display case, of a receptacle removably positionable in the case and including a horizontal top wall having a rod attached at the rear edge thereof and extending beyond the side edges of said top wall, a bottom wall having a rod secured at the rear edge thereof and extending beyond the side edges of the bottom wall, and a cover having channels at its sides slidably and pivotally engaging the ends of said first mentioned rod in the top wall and slid-

ably engageable with the ends of said rod in said bottom wall to interlock therewith, said cover being positionable by a pivotal and sliding movement either overlying said top wall or in rear of and interlocked with said bottom wall, and means on the cover engageable with said top and bottom walls acting to limit movement of the cover in either direction.
